United States Patent

Des. 234,707
Patented Apr. 1, 1975

234,707

TOY SHAPE

Jorma Vennola, Princeton, and Erkki Pekka Korpilaako,
Hightstown, N.J., assignors to Columbia Broadcasting
System, Inc.

Filed Feb. 16, 1973, Ser. No. 333,388

Term of patent 14 years

Int. Cl. D21—01

U.S. Cl. D34—15 A

FIG. 1

FIG. 2

FIG. 3

FIG. 1 is a perspective view of a toy shape showing our new design;

FIG. 2 is a side elevational view thereof; and

FIG. 3 is a bottom plan view thereof.

We claim:

The ornamental design for a toy shape, substantially as shown.
